*E. A. Locke,
Label.*

No 58847.

Patented Oct 10, 1866.

UNITED STATES PATENT OFFICE.

EDWARD A. LOCKE, OF BOSTON, MASSACHUSETTS.

IDENTIFYING-MARK FOR CASKS AND BOXES.

Specification forming part of Letters Patent No. 58,847, dated October 16, 1866.

To all whom it may concern:

Be it known that I, EDWARD A. LOCKE, of Boston, in the county of Suffolk and State of Massachusetts, have invented Improved Identifying-Marks for Wooden Casks and Cases; and I do hereby declare that the following, taken in connection with the drawing which accompanies and forms part of this specification, is a description of my invention sufficient to enable those skilled in the art to practice it.

The invention relates to a means of attaching labels or identifying-marks to wooden casks, boxes, cases, &c., the object of the invention being a provision for readily and permanently securing the labels in such position that it or the identifying-marks thereof cannot be removed by abrasion, contact, or other accidental circumstances.

The invention consists primarily in a ring or plate of metal, having identifying-marks applied to or connected therewith, such plate or ring having a lip turned down from its edge or edges in such manner or at such angle that when the plate is dropped into a depression or shallow cavity formed for its reception in the surface of the cask or case to which the plate is to be applied, and is struck a sharp blow by an instrument bearing upon its outer surface adjacent to the lip, the edges of said lip shall be forced outward or laterally into the wood, so as to confine the plate in position; also in combining with a ring so formed for attachment to a cask or case a plate or plates, or a ring or rings, so applied as to be capable of rotation in such ring, said rotary plate or plates having series of identifying or designating marks, letters, or numbers, so arranged with respect to a slot or hole made through the ring that any of the marks or numbers may be brought opposite this slot to be read through the same; also, in so applying these rotary rings that they are secured to the attaching-plate and kept in position relative thereto while being rotated.

The drawing represents a device embodying my invention, A showing an outer, and B an inner, face view thereof; C, a cross-section, half of which shows the position of the parts when applied to a cask or case. *a* denotes a ring or plate, upon the surface of which identifying or designating marks may be made, either before or after application of the plate.

b is the edge or perimeter of the plate, turned down at an angle preferably about forty-five degrees. In applying this plate a depression is made by a suitable boring-tool in the surface of the cask or case to which the plate is to be applied, of a diameter corresponding to the outer diameter of the lip upon the plate *a*, and having a depth about equal to or exceeding the thickness of the plate including the lip. The plate is dropped into this depression or cavity, and a tool is held upon its surface, so as to bear around its upper surface adjacent to the lip, the tool being so formed that by striking it a sharp blow the edge of the lip will be turned outwardly and driven laterally into the wood beyond the cavity, as seen at C. The plate is preferably made circular for convenience in boring the circular depression to receive it; but it will be obvious that it may be made rectangular, or of any other shape which may be desirable.

This is the simplest form of the invention, and instead of having the marks directly on the surface of the plate *a*, they may be on a separate central plate, to be read through a hole made in the center of the plate *a*. For using a series of identifying or designating marks, however, I make the plate *a* in the form of a ring, and apply thereto one or more circular plates, *c d*, around the edge of which are designating-marks, which may be successively brought opposite to a hole or slot, *e*, made in the plate *a*, and so as to be read through the same. When two such plates are employed, one is made rotary with respect to the other, and each with respect to the attaching-plate *a*, the edge of one, for instance, bearing in regular succession abbreviations of the months, and the edge of the other numbers designating the days of the month, so that any month and any day in connection therewith may be brought opposite to and read through the hole *e*, the rest being concealed by plate *a*.

To insure proper rotation of the plates, the plate *c* may have a circular bead struck up from it to fit the inner circular edge of the ring *a*, which may be slightly turned down, and when the plate *d* is employed the two may have beads struck up together, fitting one within the other.

To secure the identifying plate or plates to

the plate *a*, the lip *b* may be cut away, as seen at *f*, and a confining-strip, *g*, laid diametrically across the inner surface of the plate *c* or *d*, with its ends turned up and clinched over the top of the plate *a*, this confining-strip not only securing the plates together, but admitting of their free rotation with respect to each other.

The device being applied, as before described, by taking a punch and striking down a spur from the upper surface of the plate *a*, as seen at *h*, the identifying-plates are fastened in position with reference to the attached plate *a*, and so that this cannot be subsequently rotated, thus retaining in position the means of identification, which at the time of applying the device were brought into position to be read through the slot *e*.

In the attachment of revenue-marks, trademarks, or other identifying-marks, letters, or numbers to wooden casks, boxes, or cases, the simplicity and utility of these devices will be obvious. They are easily applied, are not detachable by abrasion, contact, or jar, and always afford a reliable means of ascertaining or reproducing the facts indicated by the ar-

rangement of the marks at the time of attachment.

I claim—

1. A circular or other suitably-shaped plate, provided with identifying-marks, and having a lip turned down from its edge, substantially as described.

2. The employment of a circular or other proper-shaped plate, provided with such lip, driven into the wood at the sides of the cavity or depression in which the plate is inserted, substantially as described.

3. Combining with such attaching-plate one or more rotary identifying rings or plates, operated, in connection with the attaching-plate, substantially as set forth.

4. Confining the attaching and identifying plates or rings together, so that while held together they may be respectively rotated, substantially as described.

EDWARD A. LOCKE.
